United States Patent Office

Des. 196,972
Patented Nov. 26, 1963

196,972

ELECTRIC SHAVER

Jerold R. Peterson, Roselle, and John E. Reed, Glen
Ellyn, Ill., assignors to Sunbeam Corporation, Chicago,
Ill., a corporation of Illinois

Filed July 9, 1963, Ser. No. 75,722

Term of patent 14 years

(Cl. D22—3)

Fig. 1.

Fig. 2.

Fig. 3.

FIG. 1 is a front perspective view of an electric shaver embodying our new design;

FIGS. 2, 3 and 4 are right side, rear and left side elevational views on an enlarged scale thereof, respectively; and

FIGS. 5 and 6 are top and bottom plan views thereof, respectively.

The essential features of our design reside in those portions shown by full lines.

We claim:

The ornamental design for an electric shaver, as shown and described.
